CLAIM

The ornamental design for a dental implant, as shown and described is claimed.

DESCRIPTION

FIG. 1 is a perspective view of a dental implant of the present invention;

FIG. 2 is a right side view of the dental implant shown in FIG. 1;

FIG. 3 is a front plan view of the dental implant shown in FIG. 1;

FIG. 4 is a bottom view of the dental implant shown in FIG. 1;

FIG. 5 is a left side view of the dental implant shown in FIG. 1;

FIG. 6 is a rear plan view of the dental implant shown in FIG. 1; and,

FIG. 7 is a top view of the dental implant shown in FIG. 1.
